UNITED STATES PATENT OFFICE.

ROBERT EDWARDS AND ADAM LÜNGEN, OF NEW YORK, N. Y.

ELECTRIC BELL.

SPECIFICATION forming part of Letters Patent No. 240,582, dated April 26, 1881.

Application filed July 19, 1880. (Model.)

To all whom it may concern:

Be it known that we, ROBERT EDWARDS and ADAM LÜNGEN, both of New York city, have invented certain new and useful Improvements in Electric Bells, of which the following is a specification.

The chief objects of our invention are to protect the mechanism of the bell from exposure or derangement by access of dust, moisture, or other extraneous matter, as also to enable the adjustments of the parts to be made with more convenience.

To these ends the main features of our invention consist in providing the mechanism with a completely inclosing case, having no apertures or crevices to admit extraneous matter, and also in having the adjusting-screws arranged upon the exterior of the case and extended tightly through the same, whereby all adjustments may be made from the exterior without requiring the opening of the case or the removal of any parts thereof.

Our invention also consists in the form of the armature-spring and of the adjusting-screws, and in other minor features, as hereinafter fully set forth.

In the annexed drawings, Figure 1 gives an external front elevation of the casing of the bell inclosing the mechanism thereof, the bell being removed. Fig. 2 is a similar view with the front plate of the case removed, exposing the mechanism and showing some parts in section. Fig. 3 is a side elevation, partly in section, with the bell attached.

The mechanism for vibrating the hammer of the bell and thus sounding the alarm is, as may be observed, of the usual type—that is, an electro-magnet, *a*, and a rocking armature, *b*, to the rock-shaft of which is attached the hammer *c* *d*, the current through the magnet being established through the armature and a stop-screw, *e*, against which it retires by a spring, *f*, so that the spring constantly tends to retract the armature and close the circuit, while the magnet, in turn, attracts the armature and breaks the circuit, thus producing a constant vibration in the usual manner. The adjusting-screw *e* serves to regulate the length of the armature's vibration, and the adjusting-screw *g* regulates the tension of its spring *f*, as will be readily understood.

In bells of this class heretofore the adjust-

ing devices have been placed within the case, so that a removal of part of the case is necessary to get access thereto; and, moreover, the rock-shaft of the armature and of the bell-hammer have also been placed wholly within the case, while the hammer has vibrated through an open slot therein, which, of course, admits the entrance of extraneous matter, which frequently deranges the action of the mechanism.

In our invention the adjusting-screws *e* *g*, which regulate the tension and stroke of the armature, are placed upon the exterior of the case *y*, with their stems working tightly through and into the case, to bear upon the appropriate parts of the armature inclosed within it. Furthermore, the rock-shaft or axis *h* of the armature is pivoted at its remote end in the base of the case, while its opposite or near end extends out of the case through a tight but free-fitting opening in an attached lug, *w*, on the side of the case, and the arm *c* of the bell-hammer is attached to the rock-shaft on its exterior or projecting end, and not to the portion within the case, as heretofore. Finally, the front or opening of the case is covered by a close-fitting plate, *i*, screwed to the case at suitable points, as indicated at *k*, and so formed as to completely cover the opening, and thus entirely inclose the mechanism. The joint of the plate with the case may be sealed with red lead or similar cement, if desired, to make the inclosure practically hermetical. It may therefore be readily observed that by this inclosure of the mechanism and the arrangement of the adjusting-screws and bell-hammer upon the exterior of the case the adjustments are more readily made, as no part of the case is removed therefor; and, furthermore, all openings or crevices which would admit dust, wet, or insects are entirely obviated, thus preventing any clogging of the mechanism or any interference with the internal conduction or insulation, which has been a source of frequent derangement in former constructions.

The form of the mechanism case *y* is preferably circular, as illustrated; but this is not essential, and it is preferably made of cast-iron, being cast in one piece, as shown, its base having lugs *l* *l*, by which the whole device is fixed in position. The top plate, *i*, is formed with a projecting post, *m*, to which the bell *n* is attached, and the arm of the bell-hammer is at-

tached to the rock-shaft by a set-screw, as shown, or in any other suitable manner.

The connection of the circuit-wires and the construction or mounting of the adjusting-screws, as well as the construction of the tension and contact springs of the armature, as will be observed, embody novel features. Thus the screws *e g* screw into hollow screws *o o'*, which, in turn, screw into insulating-sleeves *p p'*, which are firmly fixed in a tight-fitting opening in the side of the case. The hollow screw is held in fixed position in the insulating-sleeves by the short nuts *r r'*, screwed on either end thereof, so that the adjusting-screws turn in the hollow screws, as in a nut, and are held firmly at the desired adjustment by the jam-nuts *s s'*, which screw against the ends of the hollow screws *o o'*, as shown. Now, the circuit-wires + - connect also on the exterior of the case to the hollow screws *o o'*, being preferably clamped between the insulating-sleeves and the nuts *r r'*, as shown. It may be observed, however, that the tip of the tension-screw is provided with insulating material, *t*, where it contacts with the tension-spring *f*, while the contact-screw *e* makes metallic connection with the contact-spring *u*. The tension-screw is thus out of the direct path of the current, while the contact-screw is always in this path, the current being completed through the same. The current, therefore, enters, say, through the nut of the tension-screw, passes thence to one end of the magnet-coils, and from the opposite end of the magnet-coils flows to the tension-spring *f*, and thence, through the armature or its contact-spring *u*, to the contact-screw *e*, and off by the negative circuit-wire, which connects to its nut *r*. By this arrangement of parts it will be observed that the electrical connections to the magnet are made on the exterior of the case, through the projecting adjusting-screws or their nuts, which is a simple, convenient, and effective method. The tension and contact springs *f u* are formed of one piece of metal, preferably spring sheet-brass, bent at about right angles, curved around the rock-shaft *h*, fastened to the armature at *v*, with one end projecting toward the tension-screw to form the tension-spring and the other end extending in front of the contact-screw to form the contact-spring, this construction being obviously both simple and cheap, as well as effective.

It may be further observed from Fig. 2 that the tension-spring extends tangentially from the axis of the armature and at right angles to the armature. This form and position of the spring gives the armature great leverage over it, and the flexure of the spring is partly a winding and partly a bowing action, and its movement is found to be very quick and elastic, its flex being easy on the magnet and its reflex strong on the armature and hammer, so that a much weaker battery than usual is sufficient to produce an energetic vibration of the hammer.

It may be observed from Fig. 2 that the armature *b* does not extend centrally from the axis or rock-shaft *h*, but projects tangentially therefrom, and is fastened to the side thereof. This detail has the advantage of being more simple and convenient, and also brings the armature into close range with the magnet.

What we claim as our invention is—

1. An electric bell or alarm constructed with a case completely inclosing the ringing mechanism without opening or crevice, and having the bell placed exteriorly to the case, and an operating portion of the striking device working through said case in a tight-fitting manner, substantially as and for the purpose set forth. 75

2. The combination, in an electric alarm, of a case completely inclosing the ringing mechanism without unclosed opening or crevice, a bell mounted exterior to said case, with a rocking shaft operated by said ringing mechanism within the case, but having its outer end extended through a close-fitting bore in said case, and a bell-hammer attached to the projecting end of said rock-shaft on the exterior of the case, substantially as herein shown and described. 85

3. The combination, with an electric bell, of a case tightly inclosing the ringing mechanism thereof, and armature-adjusting screws mounted on the exterior of the case, with their stems screwing through tight-fitting nuts or tapped holes in the wall of the case, and into the interior thereof against the appropriate parts of the armature, with circuit-wires connecting exteriorly to said screws, substantially as and for the purpose set forth. 95

4. The combination, with the rocking armature *b*, of the tension and contact spring *f u*, formed of one piece of metal bent at right angles, or nearly so, and fastened at the bend to the armature, at or near the axis thereof, substantially as herein shown and described. 105

5. The combination, with an electric bell, of a case inclosing the ringing mechanism thereof, armature-adjusting screws mounted on the exterior of the said case and passing through insulating-sleeves thereinto, with circuit-wires connecting exteriorly with said screws or the nuts thereof, and internal connections from said screws or their nuts, with the magnet and armature of the inclosed ringing mechanism, substantially as and for the purpose herein shown and described. 110

6. In an electric bell in which the circuit-wires connect to the adjusting-screws of the ringing-armature, the tension-screw *g*, having an insulating-tip contacting with the tension-spring, substantially as and for the purpose set forth. 115

7. An electric bell or alarm constructed with a case permanently and completely inclosing the ringing mechanism without opening, and having the heads of the adjusting-screws and bell placed exterior to the case, and the operating portion of the hammer working through 125

a tight-fitting aperture in said case, substantially as described, and for the purpose set forth.

8. The combination, with the mechanism of an electric bell, of the inclosing-case *y*, formed in one imperforate piece, top plate, *i*, formed with the post *m*, and bell *n*, attached to said post, substantially as herein shown and described.
9. In an electric bell or alarm, the combination, with the imperforate case *y*, formed in one piece, and inclosing the ringing mechanism, and its closing top piece or cover, *i*, provided with the post *m*, carrying the bell *n*, both post and bell

lying outside of said case, of the rock-shaft *h*, 15 journaled in the base of the case and projecting beyond the outer face of the cover, lug *w*, secured to the case, and provided with an opening forming a journal-bearing for the rock-shaft, and bell-hammer *cd*, secured to the outer 20 projecting end of the rock-shaft, substantially as described, and for the purpose specified.
